Charles D. Godding

UNITED STATES PATENT OFFICE.

ADOLPH DIAMOND, OF BOSTON, MASSACHUSETTS.

COLLAR-ATTACHING DEVICE.

1,368,615.

Specification of Letters Patent. Patented Feb. 15, 1921.

Application filed December 4, 1920. Serial No. 428,230.

To all whom it may concern:

Be it known that I, ADOLPH DIAMOND, a citizen of the United States, residing at Boston, in the county of Suffolk and State 5 of Massachusetts, have invented new and useful Improvements in Collar-Attaching Devices, of which the following is a specification.

This invention relates to an improved collar attaching device.

The object of the invention is to provide a device by means of which the opposite ends of the neck band of a shirt may be attached together, and also for attaching a 15 collar to said neck band, the said device being so attached to the neck band that it will not contact with the neck.

The invention consists in the combination and arrangement of parts set forth in the 20 following specification and particularly pointed out in the claims thereof.

Referring to the drawings:

Figure 1 is a front elevation of a portion of a shirt, my improved collar attaching 25 device being illustrated attached to the neck band thereof.

Fig. 2 is a transverse section taken on the line 2—2, Fig. 1.

Fig. 3 is a front elevation of the collar 30 attaching device, the same being detached from the neck band and the cross bar thereof being located in a position to allow the device to be attached to the neck band.

Fig. 4 is a front elevation of a portion 35 of the neck band illustrating the openings therein by means of which the device is attached to the neck band.

Fig. 5 is a front elevation of a modified embodiment of my invention illustrating 40 the device adapted to be attached to the rear of a neck band in order that the rear portion of a collar may be attached to said neck band.

Fig. 6 is a transverse section taken on the 45 line 6—6, Fig. 5.

Fig. 7 is an elevation of the rear portion 50 of the neck band illustrating the openings by means of which the modified embodiment of the invention is attached to said neck band.

Like numerals refer to like parts throughout the several views of the drawings.

In the drawings, referring particularly to

Figs. 1 to 4 inclusive, 10 represents a portion of a shirt and 11 is the neck band 55 thereof. The neck band 11 is provided with a plurality of openings 12 extending partly therethrough, the said openings being constructed similar to button holes. A fastening device 13 illustrated separately in detail in Fig. 3 is adapted to be attached to the neck band 11 by being inserted within the openings 12 as illustrated in Fig. 1. The member 13 is preferably constructed of resilient sheet material and is slotted at 14 65 and 15 thereby forming a trifurcated member having furcations 16, 17, and 18, each of said slots and furcations being parallel to each other. The furcations 16 and 18 are each adapted to be inserted through 70 certain of the openings 12 and thence extend between layers of cloth 19 and 20 of the neck band and thence protrude through other openings 12 as illustrated in Fig. 1.

A cross bar 21 is pivoted at 22 to the furcation 17 and when the member 13 is being attached to the neck band, said bar is positioned longitudinally of said furcation as illustrated in Fig. 3. When, however, the member 13 is in position upon the neck 75 band, the cross bar 21 is turned on its band, the cross bar 21 is turned on its pivot 22 and sprung under the free ends of the furcations 16 and 18 to the position illustrated in Fig. 1, at which time a portion of cloth 23 between the openings 12 will 80 prevent the member 13 from being removed from the neck band. A button 24 is securely fastened in any desired manner to the furcation 17 and to this button the opposite end of the neck band may be attached, after which said button may be utilized to secure a collar to the neck band 90 in the well known manner.

The manner in which the device is used is as follows:—With the cross bar 21 positioned relatively to the furcation 17 as illustrated in Fig. 3, the furcations 16 and 18 are inserted through a pair of openings 12 and thence extend a short distance between layers 95 19 and 20 of the material forming the neck band to another pair of openings 12 through which they protrude. The cross bar 21 is then turned and sprung under the free end of the furcations 16 and 18, thereby preventing said furcations from there- 100 after being pulled through the openings 19, 105

and the member 13 from being removed from the neck band. The opposite ends of the neck band may then be fastened together by means of the button 24 after which the collar may also be attached to the button.

In Figs. 5, 6 and 7 I have illustrated a modified embodiment of my invention, the said embodiment being more particularly 10 adapted for use in attaching a collar at the back of the neck band. In this embodiment, the neck band 11 is provided with a pair of openings 25 and 26 formed in a manner similar to button holes. A fastening device 15 27 constructed of resilient sheet material is slotted at 28 and 29, thereby forming furcations 30, 31 and 32. A cross bar 33 is pivoted at 34 to the free end of the central furcation 31 and when it is desired to fasten 20 the member 27 to the neck band, the opposite end portions of the cross bar are preferably sprung over the free ends of each of the furcations 30 and 32. A projection 35 extends outwardly a short distance from 25 the lower edge of the furcation 32 and is then bent to project downwardly a short distance, thereby providing a means which may project through the button hole provided in the rear of a collar and the collar 30 is fastened to the neck band thereby. This embodiment of my invention is attached to the neck band 11 in a manner similar to the member 13 previously described. When the shirt is laundried the fastening devices 35 are removed from the neck band, being again attached to the neck band when it is desired to again use the shirt. When the device is attached to the neck band no portion thereof will contact with the neck and 40 for this reason the neck can not be soiled or become discolored thereby.

I claim:

1. In combination, a shirt, a neck band therefor provided with a plurality of openings therein, a trifurcated member adapted to be inserted within said openings, means to prevent the removal of said member from said openings and means to attach a collar to said member.

50 2. The combination with a neck band having a plurality of openings therein of a resilient trifurcated member adapted to be inserted within said openings, means to prevent the removal of said member from said 55 openings and means to attach a collar to said member.

3. The combination with a neck band having a plurality of openings therein of a trifurcated member adapted to be inserted 60 within said openings, means attached to one of the furcations of said member adapted to prevent the removal of said member from said openings and means to attach a collar to said member.

4. The combination with a neck band 65 having a plurality of openings therein of a trifurcated member adapted to be inserted within said openings, means attached to the central furcation of said member adapted to prevent the removal of said member from 70 said openings and means to attach a collar to said member.

5. The combination with a neck band having a plurality of openings therein of a trifurcated member adapted to be inserted 75 within said openings, means pivotally attached to the central furcation of said member adapted to prevent the removal of said member from said openings and means to attach a collar to said member.

6. The combination with a neck band having a plurality of openings therein of a trifurcated member adapted to be inserted within said openings, means pivoted to the central furcation of said member adapted to 85 engage the material of said neck band between said openings and thereby prevent the removal of said member from said openings and means to attach a collar to said member.

7. The combination with a neck band having a plurality of openings therein of a resilient member having a plurality of furcations formed integral therewith, alternate furcations projecting through said openings 95 and extending between the layers of material forming said neck band, means pivoted to the central of said furcations adapted to prevent the removal of said furcations from said openings and means to attach a collar to 100 said member.

8. The combination with a neck band having a plurality of openings therein of a resilient member having a plurality of furcations formed integral therewith, the outer 105 of said furcations projecting through said openings and extending between the layers of material forming said neck band, means pivoted to the central of said furcations adapted to prevent the removal of said outer 110 furcations from said openings and means to attach a collar to said member.

9. The combination with a neck band having a plurality of openings therein of a resilient member having a plurality of furcations formed integral therewith, the outer 115 of said furcations projecting through said openings and extending between the layers of material forming said neck band, means pivoted to the central of said furcations 120 adapted to prevent the removal of said outer furcations from said openings, and a button attached to said central furcation.

10. The combination with a neck band having a plurality of openings therein of a 125 resilient member having a plurality of furcations formed integral therewith, the outer of said furcations projecting through said

openings and extending between the layers of material forming said neck band, a cross bar pivoted to the central of said furcations adapted to overlap the ends of said outer furcations and thereby prevent the removal of said outer furcations from said openings and a button attached to said central furcation.

In testimony whereof I have hereunto set my hand in presence of two subscribing 10 witnesses.

ADOLPH DIAMOND.
